UNITED STATES PATENT OFFICE.

CONRAD R. STRASSNER, OF LYNBROOK, NEW YORK, ASSIGNOR TO ATLANTIC KNITTING MILLS, INCORPORATED, OF NEW YORK, N. Y., A CORPORATION OF NEW YORK.

DESIGN FOR KNITTED FABRIC OR SIMILAR ARTICLE.

Application filed December 29, 1923. Serial No. 8,185. Term of patent 3½ years.

To all whom it may concern:

Be it known that I, CONRAD R. STRASSNER, a citizen of the United States, residing in Lynbrook, Long Island, State of New York, have invented a new, original, and ornamental Design for Knitted Fabric or Similar Article, of which the following is a specification, reference being had to the accompanying drawing, forming a part thereof, wherein the figure is a plan view of a fabric embodying the design.

What I claim is:

The ornamental design for knitted fabric or similar article as shown.

CONRAD R. STRASSNER.
